GENERATION OF GASEOUS CO₂

Joseph C. Dittmer, St. Albans, N. Y., assignor to
 National Lead Company, New York, N. Y., a
 corporation of New Jersey

Application December 9, 1939, Serial No. 308,324

14 Claims. (Cl. 62—91.5)

The invention is a system for deriving gaseous carbon dioxide in required quantity from a reservoir containing that material, or a material of like thermodynamic properties, in non-vapor phase, and consists broadly in a method and means for applying heat to such material to produce the conversion to gas at low cost and at a required useful rate and the delivery of such gas at a proper temperature under practical pressure conditions and sensitive control, as below disclosed and explained.

The accompanying drawing gives an exemplification of the new system and the principles thereof in the form at present preferred, but without limitation thereto.

In this drawing, which is essentially diagrammatic, the space marked 1 symbolizes the place of delivery or consumption of the generated gas and may be taken to be any tank or a carbonating process or other system requiring a continuous or intermittent supply of gas herein referred to as the load demand.

The gas is furnished to this process by a delivery line 2, including a main valve 3 and chamber 4, from a closed reservoir 5. This reservoir may be of ordinary tank or boiler design capable of pressures of the order of, say, 400 pounds or less, with an appropriate safety factor and may be large enough to hold, for example, 4000 pounds or more of carbon dioxide which may be placed therein in solid form, that is, in the form of cakes of dry-ice, indicated at 6. It is closed by a standard manhole cover 7 at its top and is well heat-insulated by appropriate lagging as indicated.

If such insulated reservoir were subject externally only to atmospheric temperatures, the dry-ice therein would convert to vapor too slowly for practical purposes and heating is therefore necessary. According to this invention such heating is effected by convection to the reservoir contents from a heat source which is removed from the reservoir. For this purpose the reservoir 5 is included in a circuit with the jacket chamber 8 of a heater element 9, such chamber being connected at its top by one or more valve-controlled pipe connections 10 and 11, of ample dimensions, to one or more points above the bottom of the reservoir, and by a pipe connection 12 with the very bottom of the reservoir.

Any source of heat can be used but steam is preferred, because of its convenience and economy, in which case the heating element 9 is a steam compartment receiving steam from a jet pipe 13 therein under the control of an electric steam valve 14 presently referred to. This steam

compartment 9 is vertically disposed inside the heater jacket and so relatively dimensioned as to provide a heating chamber of thin annular section and relatively small capacity as compared to the much larger reservoir. The lower end of the steam compartment depends well below the chamber 8 where it may be provided with, or connected to a compartment extension or sump 15 which is connected to the waste by a drain line and steam trap 16 as indicated. The dioxide contents of the heating chamber being normally colder than 32° F., this downward extension of the steam compartment affords the advantage that water condensing out of the steam falls or flows quickly out of the cold region before it can freeze, and into the warmer region below, whence it escapes by the drain. The jet pipe 13 has a drain hole 17 near its bottom so that any water in it, as on a cessation of the steam supply, may also drain promptly away. The shape and position of the condensate part of the steam compartment, whether it includes a connected sump as indicated or whether it is directly connected to steam trap, or otherwise, is of no special consequence so long as this important effect is preserved. Connecting the sump to the condensate part of the steam compartment by a narrow conduit, such as suggested at 18, affords an additional safeguard against the freezing of any accumulated condensate because such a connection offers but a small metallic cross-section for the flow of heat from it to the colder parts above. Still further safety from the freezing of the condensate may be had by jacketing the sump and connecting the jacket directly to or between the steam supply and the steam trap, so that a small amount of steam will continuously pass through the jacket keeping the sump warm and radiating a slight amount of heat to the un-insulated bottom of the lower or condensate part of the steam compartment directly above it. By the above method of steam-heating the carbon dioxide, which is obviously quite independent of the nature of the chamber in which such dioxide is contained, the danger of stoppage or delay from freezing is completely and simply eliminated.

On starting up the system, steam-heated gas rises from the chamber 8 into one or the other or both of the pipe connections 10 or 11, assuming their valves to be open, and flows over the dry-ice in the reservoir warming it, while cooler gas in the reservoir passes into the heater through the bottom connection, thus forming a gas circulation. The heat thus carried by the gas

from the steam to the dry-ice causes it to sublime more rapidly and increases thereby the pressure in the reservoir. The rate of heat transfer is dependent on the size and temperature of the heater element and to some extent on the dimensions of the circulatory path and these factors can of course be adjusted according to the needs in hand.

For some purposes, the rate of sublimation thus produced might be sufficient to supply the gas required by the process 1, but in many cases a higher delivery rate is required and to that end, according to this invention, the main valve 3 is kept closed until continued sublimation, under the effect of the circulatory heating, has raised the reservoir pressure to about 70 pounds absolute and the temperature of at least some of the dry-ice, from its natural temperature (about -110° F.) to a temperature of -69.83° F. at which so-called triple-point, the dry-ice begins to melt into liquid carbon dioxide. The heating chamber 8 is installed at a lower level than the reservoir so that the liquid flows into it by gravity and at once, and as soon as this occurs, gas is produced by evaporation in the heated chamber, supplementing that produced by the sublimation and at a much greater rate, the gas circulation being of course interrupted when the bottom pipe 12 becomes more or less filled with liquid. Main valve 3 can presently be opened and delivery of gas begun.

This is not done until some selected delivery pressure, above 70 pounds absolute, has been attained, say about 200 pounds gauge, and thereafter the application of heat to the chamber 8 is regulated to evaporate the liquid therein at such rate as to satisfy the load demand and at the same time maintain about that pressure in the reservoir. Such rate is desirably so ordered that the temperature of the delivery gas is above 32° F., as this avoids objectionable atmospheric frosting on the delivery line.

The gas may go to the demand directly from the riser pipe 11 if there is sufficient liquid reserve in reservoir 5, but is preferably led through the tank, as illustrated, so that some of its heat may be imparted to the reservoir contents to continue the heating and melting of enough of the remaining dry-ice therein to keep chamber 8 supplied with just sufficient liquid CO_2 for converting into the CO_2 gas at the desired rate of consumption. Any excess is unnecessary and undesirable.

This method of continuing the supply of heat to the reservoir contents, after gas circulation has ceased, may suffice to convert gradually all of the remaining dry-ice to liquid and at a rate required to keep the heater constantly supplied with liquid, but in the event that this rate is not sufficiently accomplished, as might be the case, for example, with a very tall and narrow reservoir, a further heating means is available, within the scope of this invention, by opening the chamber connection 10 which is located at such level as to be capable of returning liquid dioxide, warmed by the heater, back into the reservoir through which it may then circulate in the same manner as the gas initially circulated. Liquid dioxide is a more effective heat carrier than gaseous dioxide so that the transfer of heat is accelerated, in fact, increased many fold. For instance, with a heater element of two feet radiation and steam at 65 pounds, about 400,000 B. t. u. per hour can be exchanged, with steam flowing continuously and this will suffice to heat the res-

ervoir as required while maintaining an abundant delivery at about 200 pounds. Under the gas circulation only about 6500 B. t. u. are exchanged. Since the liquid boils violently in the evaporating chamber at the pressure stated, much of it,

5 according to the principle of the air lift, will be carried upwardly to or above and through the connection 10. Circulation begins at once on opening the valve 10, which valve may then be regulated to control the rate of transfer. Thus the reservoir, which is heavily insulated against absorbing heat from atmosphere, is arranged to receive heat from the small chamber either by gas or liquid convection, but only to the extent requisite to melt the dry-ice and without causing higher allowable working pressures than those which the reservoir construction can safely confine.

20 So long as dry-ice remains in the reservoir, its low temperature (-110° F. to -70° F.) during operation serves to keep any liquid therein so cold that evaporation of such liquid is sluggish, and in fact occurs only as the heat insulation leaks atmospheric heat to the interior of the reservoir. 25 It is possible when there is much cold dry-ice (at or about -110° F.) present and the steam has been shut off, for some of the liquid to freeze again in the reservoir by the heat absorption of the dry-ice in warming up to the equilibrium 30 temperature. Whatever gas is evolved therein as the result of insulation leakage or of heat derived from the evaporating chamber passes to the delivery line to supply part of the demand.

35 Chiefly, the load demand is carried by the evaporation in the small chamber which, because of its small capacity, is peculiarly suited to sensitive regulation, by control of the heating medium. This may be done by graduating the steam admission or by intermittently cutting it 40 in and out as preferred for the case in hand and similarly for any other form of heating medium.

During standby periods when there is no withdrawal for consumption and no refrigerating effect incident to a falling pressure in the system 45 and perhaps no residual ice in the reservoir to exert a refrigerating effect, excessive reservoir pressure (due to absorption of atmospheric heat) is avoided and rendered impossible by several means; first, by a spring-loaded blow-off or safety valve, indicated at 19, which is set to open, for example, at 325 pounds. A momentary venting of gas by this valve checks any rising tendency of the reservoir pressure by stimulating evaporation of the liquid therein, and correspondingly chilling the remaining liquid, so that the pressure is at once restored to a lower value.

In addition to, or substitution for, this means of refrigerating the reservoir contents, a mechanical refrigerating unit can be employed, and is preferably employed, as represented by the refrigerator coil 20 located within the chamber 4 connected in the supply line. This is merely the expansion coil of an ordinary refrigerating unit 50 conventionally shown. By its use the gas in the chamber 4 is condensed and liquefied and returned back to the main body of liquid with of course an attendant lowering of the pressure in the reservoir, and with no venting of gas.

55 Final safeguard against excessive pressures in the reservoir is provided, as customary in the handling and storage of liquefied gases by a second safety vent 22 normally closed by a rupturable disc designed to yield to a pressure of, say, 550 pounds, which is a lower rupture pressure than customary for commercial flasks of liquefied

carbon dioxide. Valved connection 23 represents a branch delivery line or a manifold to which other generators may be connected and also a means of exhausting residual gas in order to drop the pressure to atmospheric so that reservoir 5 can be opened for refilling.

The coordination of the rate of heating to the rate of gas delivery so as to maintain substantially constant pressure conditions in the reservoir, is accomplished automatically and preferably by means of two mercoid pressure switches, 24 and 25, both connected by pipe line 26 to the reservoir or its delivery line 2, to be operated by pressure fluctuations therein and having appropriate electrical connections as indicated. Pressure switch 24 controls the steam valve 14, through a solenoid or equivalent motor device, shown as incorporated in the valve, and is ordinarily set to close its circuit and open that valve at, say, 200 pounds, and to open its circuit to close the valve at, say, 225 pounds, or as desired. This will suffice to keep a sufficiently constant reservoir pressure for many uses, but the regulation can be set to as close a margin as the sensitivity of the instruments permit.

Pressure switch 25 is ordinarily set to close its circuit and start the refrigerating unit 21 in action at about 290 pounds reservoir pressure and to open its circuit and stop the unit when such pressure has been reduced to, say, 275 pounds.

As thus set, the refrigerating unit will not be likely to be often called into action during normal operation but is available if needed. During overnight or standby periods when refrigeration from residuary dry-ice is insufficient, it may come more frequently into operation, depending of course on the efficiency of the heat insulation applied to the reservoir.

It may be observed that the system described is competent to produce a controlled delivery of gaseous carbon dioxide at a constant or variable rate from a reservoir kept always at moderate pressure, not in any event higher than commonly found in steam boilers and which can be safely accommodated in reservoirs of commensurate cost. In carbon dioxide gas generators heretofore commercially used, so far as I am aware, the supply reservoirs have consisted either of the familiar high pressure flasks or cylinders of liquid CO₂ of a maximum of 75 pounds capacity, or of specially strong and very expensive tanks also of small capacity in which dry-ice has been confined and caused to sublime or melt, by heat directly applied to the tanks. In these receptacles the expected pressures are high and variable and the rate of gas generation is not satisfactorily controllable, or the delivered gas is too cold, and the cost in any event is so high as to be prohibitive for many commercial uses for which carbon dioxide is desirable. The new system herein described and below broadly claimed, because of its larger reservoir and sensitive evaporation control minimizes those objections and difficulties.

I claim:

1. A method of deriving gaseous carbon dioxide or like gas from an insulated reservoir holding such material in solid form which comprises first circulating the gas attendant on such material through a small heating chamber until some of the solid in the reservoir has melted to liquid phase, then circulating this liquid through a heating chamber and the reservoir until a desired pressure has been established in the reser-

voir, thereafter maintaining the liquid in the reservoir at a temperature adapted to restrain evaporation thereof at said pressure, and coincidentally delivering gas from said heating chamber to the load demand at a temperature higher than that of any gas evaporating from said reservoir liquid.

2. The method of deriving gaseous carbon dioxide from a reservoir containing and confining such material in solid form, which comprises first circulating the gas present with the solid dioxide through a separate heating chamber and back to the reservoir until some of the solid dioxide has melted to liquid, and the reservoir then contains both liquid and solid dioxide, then circulating this liquid from the reservoir through a heating chamber and back to the reservoir thereby carrying heat to the reservoir by liquid convection to melt more of the solid dioxide and, while thus melting the solid dioxide in the reservoir, withdrawing directly from said chamber the gas produced by the effect of the heat applied in said chamber.

3. The method of deriving gaseous carbon dioxide from a reservoir containing that material in solid form, which comprises first circulating the gas present in the reservoir through a separate, small heating chamber and back to the reservoir until some of the solid therein has melted to liquid form, then circulating this liquid from the reservoir, instead of the gas therein, through the same heating chamber and back to the reservoir, thereby transferring heat by liquid convection to the solid therein, and withdrawing gas developed during such liquid circulation to the place of use.

4. The method of deriving gaseous carbon dioxide from a reservoir containing that material in solid form, which comprises first establishing a thermal circulation of the gas present in the reservoir through a separate, small heating chamber and back to the reservoir until some of the solid therein has melted to liquid form, then establishing a thermal circulation of this liquid through the same heating chamber until more of the solid has been melted and a desired delivery pressure has been developed in the reservoir, coincidentally withdrawing gas from the circulation to satisfy the load demand and in the meantime varying the application of heat to said heating chamber to maintain said reservoir pressure during such withdrawal.

5. The method of deriving carbon dioxide gas from a low pressure reservoir containing carbon dioxide in non-vapor phase which comprises constantly maintaining such reservoir by means of adequate insulation and refrigeration under desired low temperature and pressure conditions, circulating carbon dioxide gas or liquid from such reservoir through a separate steam-heated heating chamber and back into the reservoir to melt any solid carbon dioxide therein, passing liquid carbon dioxide by gravity from the reservoir to the separate heating chamber to gasify it at a predetermined rate to meet the required demand for gas, and allowing some of the generated gas to flow into the reservoir.

6. The method of deriving carbon dioxide gas from a heat insulated reservoir containing such material in solid form which comprises heating the reservoir contents by circulating the gas present with the solid carbon dioxide, through a separate heating chamber and back into the reservoir until some liquid dioxide forms, then piping the liquid through the same heating chamber

and reservoir in circulatory fashion, sufficient heat thus being transferred first, to convert some solid into liquid, second, to convert sufficient of the liquid into gas in order to build the pressure of the reservoir up to a selected range above 70 lbs. absolute, and third, to produce sufficient gas to supply the load demand within the range of pressures desired and regulating the heating conditions affecting said chamber during gas withdrawals to maintain such selected pressure.

7. A system of the kind described comprising a reservoir adapted to contain carbon dioxide or like material in non-vapor form, a separate small chamber connected in circulatory relation to said reservoir, means for applying heat to said chamber, the outlet connection of said chamber including a passage located for returning liquid to the reservoir and another for returning gas thereto.

8. A system for supplying gaseous carbon dioxide comprising a low-pressure reservoir adapted for containing liquid dioxide and entirely encased in a heat insulating jacket and having means in addition to such insulation for maintaining therein a low temperature at a pressure high enough to inhibit evaporation at such temperature, a small chamber connected to said reservoir receiving liquid dioxide therefrom, a source of heat applied to said chamber for evaporating the liquid therein, and a gas delivery pipe extending from such chamber to the place of gas consumption.

9. A system for supplying gaseous carbon dioxide comprising a reservoir adapted for containing liquid dioxide entirely encased in a heat insulating covering and having means in addition to such insulation for maintaining a low temperature and a pressure therein of not more than several hundred pounds suited to inhibit evaporation of the liquid at such temperature, a small chamber connected to receive liquid dioxide from said reservoir, a source of heat applied to said chamber to evaporate part of such liquid therein, a gas delivery pipe from said chamber and means for returning excess liquid from said chamber or pipe back to the reservoir.

10. A system for supplying carbon dioxide or like gas from a reservoir containing such material in non-vapor form, comprising a separate, small heating chamber disposed at a lower level than such reservoir, piping connecting the bottoms of said chamber and reservoir, a gas off-take from said chamber to the place of use having a branch communication with the reservoir at a low point on the latter adapted to permit liquid circulation from said chamber back to the liquid in the reservoir, and means for varying the delivery of heat to the circulated liquid in accordance with the load demand.

11. A system for supplying carbon dioxide or like gas from a reservoir containing such material in non-vapor form, comprising a separate, small heating chamber disposed at a lower level

than such reservoir, piping connecting the bottoms of said chamber and reservoir, a gas off-take from said chamber to the place of use having two branch communications with the reservoir, one at a low point on the latter adapted to permit liquid circulation from said chamber back to the liquid in the reservoir, and the other at a higher point adapted to pass heated gas into the reservoir.

12. Apparatus for supplying gaseous carbon dioxide comprising a heat insulated reservoir adapted for containing non-vapor form carbon dioxide and maintained under desired vapor pressures by means of low temperatures adapted to restrain transition to vapor form, an evaporating chamber connected to receive liquid dioxide from the reservoir, and means for heating said chamber comprising a steam compartment therein having its lower part extended far enough to the outside of said chamber to avoid freezing of the condensate and a jet pipe for delivering steam to the compartment, said compartment and jet pipe being both provided with drain communications for water of condensation also located outside said chamber.

13. A system for supplying gaseous carbon dioxide or like gas, comprising a reservoir adapted for holding such material in non-vapor form and normally at a temperature less than 32° F., a small chamber connected in circulatory relation to such reservoir, and means for applying steam to heat such chamber comprising a vertical compartment having its upper part exposed to the temperature of the medium circulating through said chamber, and its lower part extended away from such chamber, means associated with this lower part for maintaining it at a temperature above 32° F., said compartment being shaped to permit water of condensation to pass freely into the lower part thereof, and means connected to the lower part of said compartment for admitting steam thereto and for removing condensate therefrom.

14. A system for supplying gaseous carbon dioxide or like gas, comprising a reservoir adapted for holding such material in non-vapor form at a normally prevailing temperature of less than 32° F., a small chamber connected to such reservoir to receive liquid dioxide therefrom, said chamber being constituted of a casing surrounding a vertical steam compartment so as to form therewith a shallow, annular passage for the flow of dioxide, the upper part of said compartment being exposed to the temperature of the dioxide flowing in said passage and its lower part being extended downwardly from such passage, means associated with this lower part for maintaining it at a temperature above 32° F., means for causing a hot vapor to ascend in said compartment and means in the lower, warmer part of said compartment for collecting the vapor condensate.

JOSEPH C. DITTMER.
